W. H. BENEDICT

CLOSURE FASTENER

Filed Feb. 14, 1924

William H. Benedict
INVENTOR.

Patented Nov. 2, 1926.

UNITED STATES PATENT OFFICE.

WILLIAM H. BENEDICT, OF SOUND BEACH, CONNECTICUT.

CLOSURE FASTENER.

Application filed February 14, 1924. Serial No. 692,708.

This invention relates to apparatus for automatically securing a slidable closure against movement when an attempt is made to open the same.

5 Among the objects of this invention are to provide a device of the above class which can be applied to or removed from the closure without disassembling or in any way altering the same and without the use of 10 the usual attaching means (such as screws, nails, or screw clamps), which when removed leave no visible marks; which securely holds the closure against movement in either direction, and which is of few parts, 15 simple in construction and adapted to be made and sold at a low price.

In order that the nature of my invention may be clearly understood the same is described with reference to the accompanying 20 drawings illustrating the same, in which:

Fig. 1 is a side elevational view of a device embodying the invention in position upon a window, the dotted outline indicating the position of the parts when the window is 25 locked against movement;

Fig. 2 is a view similar to Fig. 1 showing a different form of engaging member with the parts in operation or locked position;

Fig. 3 is a perspective view of a preferred 30 form of the invention in which the bracket is constructed from a single piece of sheet material.

Fig. 4 is a rear elevational view of the device shown in Fig. 3;

35 Fig. 5 is a plan view of the blank for the bracket;

Fig. 6 shows the bracket blank after the first bending operation;

Fig. 7 is a plan view of one means of connecting the engaging member to the bracket;

Fig. 8 is a perspective view showing the invention in operation;

Fig. 9 is a longitudinal sectional view showing a different form of resilient buffer.

45 The invention is adapted for use on any sort of sliding closure, but for the purpose of illustration is shown as applied to the lower sash A of a window. The invention comprises a bracket 9 resting upon the upper cross piece of the window sash and secured thereon in a manner later to be described. The bracket is provided with a wedging face 50 10 between which and a fixed or stationary upright, which may be the side frame of the 55 upper window sash B, an engaging member

such as the block 11 or the roller 11^a (Fig. 2) is adapted to be wedged.

While the engaging member 11 or 11^a may be of solid material such as hard wood or metal with a knurled or otherwise roughened surface, to prevent mutilation of the engaged surface, the member preferably is of or at least faced with any suitable resilient material which will give good frictional resistance such as rubber or a rubber compound. To force the engaging member 11 outward and thus increase the hold of the same upon the upright a resilient buffer is interposed between the engaging member and the bracket 9. This resilient buffer may be a swinging block 12^a (Fig. 9) pivoted to the bracket at 12^b and yieldingly forced to the limit of its outward movement by a spring 12^c retained in place by a stop pin 12^d which limits the inward movement of the block to a 75 position wherein the engaging face of the block substantially coincides with the wedging face of the bracket; but the buffer preferably takes the form of a flat spring or tongue 12, (Figs. 1 and 2) secured to the 80 bracket adjacent to the top of the wedging surface 10 and normally disposed in spaced relation thereto. This resilient buffer is an important feature of the invention in that it effects positive and adequate engagement of 85 the member 11 or 11^a with the upright of sash B.

So far as the efficient operation of the fastener is concerned no connection between the engaging member 11 or 11^a and the bracket 9 is required, but to prevent such member from being lost and to permit it to be easily moved to and from operative position, some means of connection is desirable, and this connection may be utilized to serve as means 90 of restraining the engaging member against retrograde movement along the wedging face of the bracket. The form of connection illustrated is that of a bail shown in plan Fig. 7. The restraining function above noted may be accomplished by providing elongated recesses 14 in the opposite sides of the bracket 9 into which the pivot ends 13^a of the bail 13 are received, one side of the recesses being formed with ratchet teeth 14^a 100 adapted to be successively engaged by the pivot ends 13^a as the engaging member 11 or 11^a works down into the wedging groove. (See Figs. 1, 2, 3 and 9 also Figs. 8.)

ber 11 and its connection 13 when in locking position are shown in Fig. 8 and in dot and dash outline in Fig. 1. Easy and quick attachment of the bracket 9 to the closure without the use of the usual attaching means such as screws, nails and clamps is provided by a depending arm 15 having an upturned spur 16. The arm preferably depends from the bracket at a slightly rearward angle and the spur projects upwardly and rearwardly at an acute angle from the arm as illustrated in Figs. 1 and 2. The bracket 9 is hooked over the top bar or top rail of the window, with its base resting on the bar and the arm 15 engaging the outer upright face thereof. As the engaging member 11 is forced downwardly into the wedging space, bracket 9 is forced back in place on the top rail of closure A and the spur engages the outer face thereof securing a tight grip on it if the rail is of metal, and sinking into it if it is of wood.

Altho the fastener will operate efficiently if the wedge face 10 and the resilient abutment 12 have a substantially straight surface, I may prefer to make the same curved and to secure quick wedging action of the engaging member 11 and a greater area for frictional contact between it and the wedging surface of the bracket 9 and the opposed fixed surface by forming engaging member 11 as an eccentric wedge with curved engaging faces, the inner one 17 of which conforms substantially to the curve of the wedging face 10. The outer engaging surface 18 of the eccentric wedge may be on the same radius but from a different center.

In the broader aspects of the invention, the bracket 9 may be made either solid or hollow, of wood, metal or other suitable material formed in any desired manner and may have the depending arm 15 and the resilient abutment 12 secured thereon. I prefer, however, to blank the entire bracket from sheet material, bending the same to the required form in the fewest possible number of steps and thus making the spurred depending arm of the resilient buffer as integral parts of the bracket. Such a blank before bending is illustrated in Fig. 5, the bends to be made being indicated by dotted lines. The portions of the blank which form the sides of the bracket have lips 19 which are bent beneath the portion 20 which forms the base of the bracket thereby locking and retaining the bracket in its final shape. For greater strength, these lips 19 may be soldered, welded, or otherwise securely fastened to the base 20. As will be evident from Fig. 5, the portion of the blank which forms the resilient buffer or spring tongue 12 is of such width as to engage the ends of the sides of the bracket which in this modification of the invention form the wedging surface 10, of the bracket. Fig. 6 shows the bracket after

the first bending operation and Figs. 3 and 4 disclose the completed device. While a single spur on the depending arm might be sufficient, a plurality of spurs and a consequent better hold is produced by serrating 70 the bottom edge of the depending arm 15 prior to bending.

Having now described my invention and the manner of its use, what I claim is:

1. A fastener for slidable closures comprising a bracket adapted to be secured to the closure, an engaging member, a resiliently mounted member interposed between said bracket and said engaging member and against which the latter is adapted to be 75 forced, and a rigid abutment for said resiliently mounted member for rendering said engaging member effective to restrain said closure against movement in one direction.

2. A fastener for slidable closures comprising a bracket adapted to be secured to the closure and presenting a convex wedging surface, an engaging member, and a resiliently mounted member interposed between 80 said surface and said engaging member and against which the latter is adapted to be forced to restrain said closure against movement.

3. A fastener for slidable closures comprising a bracket adapted to be secured to the closure and presenting a wedging surface, an engaging member, and means urging 85 said member away from said bracket when said member is in operative or locking position.

4. A fastener for slidable closures comprising a bracket adapted to be secured to the closure and presenting a wedging face, an engaging member, and a resilient tongue 105 interposed between said member and said bracket and adapted to be forced against said bracket when said member is in locking position.

5. A fastener for slidable closures comprising a bracket adapted to be secured to the closure and presenting a convex wedging face, an engaging member, and a resilient tongue arranged continuously to force 110 said member away from said bracket, whereby said tongue coacts with said member and the opposing surface engaged thereby to force said member into closure locking position.

6. A fastener for slidable closures comprising a bracket adapted to be secured to the closure, a strip of string material secured at one end to said bracket and forming a resilient tongue normally spaced from one face of said bracket, and an engaging member arranged to be wedged against said tongue to force said strip into engagement with said bracket face thereby to lock said closure against movement.

7. A fastener for slidable closures comprising a bracket adapted to be secured to 120

- the closure, an engaging member having a pivoted connection with said bracket, a yielding abutment between said member and said bracket, and means automatically adjusting the connection between said member and said bracket as the former is wedged against said bracket to lock the closure against movement.
8. A fastener for slidable closures comprising a bracket adapted to be secured to the closure, an engaging member, a yielding abutment between said member and said bracket and against which said member is adapted to wedge, and means automatically adjustable in response to yielding movement of said abutment for resisting movement of said member to release said closure.
9. A fastener for slidable closures comprising a bracket adapted to be secured to the closure, and having a curved engaging face, and an eccentric wedge arranged to be wedged against said face, the sides of said wedge being curved and of substantially the same radius as said face.
10. A fastener for slidable closures comprising a bracket secured to the closure and having a wedging face, a member arranged to be wedged against said face on movement of said closure, and means engaging said bracket adjacent said face for holding said member against retrograde movement along said face whereby the closure is locked against movement.
11. A fastener for slidable closures comprising a bracket secured to the closure and having a wedging face, a member arranged to be wedged against said face on movement of said closure, and means automatically adjustable in response to movement of said member along said face for holding said member against retrograde movement along said face whereby the closure is locked against movement in either direction.
12. A fastener for slidable closures comprising a bracket secured to the closure and having a wedging face, a member arranged to be wedged against said face on movement of said closure, and means automatically adjustable in successive steps in response to movement of said member along said face for holding said member against retrograde movement along said face whereby the closure is locked against movement.
13. A fastener for slidable closures comprising a bracket secured to the closure and having a wedging face, a member having a pivotal connection with said bracket arranged to be wedged against said face, and ratchet means cooperating with said connection for restraining said member against retrograde movement along said face.
14. A fastener for slidable closures comprising a bracket having a wedging face, and a member arranged to be wedged against said face, said bracket having a depending arm provided with a spur for securing the bracket to the closure in response to the wedging of said member against said face.
15. A fastener for slidable closures comprising a bracket having an angularly disposed depending arm provided with an upturned spur, a wedging face above said arm, and a member arranged to be wedged against said face to lock the closure against movement, the wedging action of said member upon said face causing said spur to secure the bracket upon the closure.
16. A fastener for slidable closures comprising a bracket having an angularly disposed depending arm provided with an upturned spur, a wedging face above said arm, said arm, spur and face being integral with said bracket, and a member arranged to be wedged against said face to lock the closure against movement, the wedging action of said member upon said face causing said spur to secure the bracket upon the closure.
17. A fastener for slidable closures comprising a bracket blanked from sheet material and bent to shape and providing a wedging face and a spurred depending arm, and an engaging member pivotally mounted on said bracket and arranged to be wedged against said face, the wedging action serving automatically to force said spurred arm into bracket securing engagement with the closure.
18. A fastener for a slidable closure comprising a bracket blanked from sheet material bent to shape and having side portions provided with lips engaging beneath the bottom portion of the bracket to secure the parts against distortion, said side portion forming a wedging face and said bottom portion having a spurred depending arm, and an engaging member pivotally mounted on said bracket and arranged to be wedged against said face.
19. A fastener for slidable closures comprising a bracket adapted to be secured to the closure and presenting a wedging face, an engaging member pivotally mounted on said bracket, the pivotal connection being movable substantially in parallelism with said face to permit movement of said member along said face.
20. A fastener for slidable closures comprising a bracket adapted to be secured to the closure and presenting a wedging face, an engaging member, a bail securing said member to said bracket for pivotal movement, said bail engaging elongated recesses in said bracket in substantial parallelism with said face thereby to permit movement of said member along said face.
21. A fastener for slidable closures comprising a bracket adapted to be secured to the closure and presenting a wedging face, an engaging member, a bail secured to said

member and having parts received in toothed elongate recesses in said bracket, whereby said member is pivotally mounted for swinging movement into or out of operative position and permitted to move along said face into wedging contact therewith, said bail ends and said toothed recesses cooperating automatically to maintain said member in wedged position.

22. A fastener for slidable closures comprising a bracket adapted to be secured to the closure and presenting a wedging face, an engaging member, a bail secured to said member and having parts received in elongate recesses in said bracket having serrated faces, said recesses being adjacent said face and in substantial parallelism therewith.

23. A fastener for slidable closures comprising a bracket adapted to be secured to the closure and presenting a wedging face,

an engaging member pivotally mounted on said bracket, the pivotal connection being movable relative to said face to permit movement of said member along said face, 25 and yielding means urging said member away from said face.

24. A fastener for slidable closures comprising a bracket adapted to be secured to the closure and presenting a wedging face, 30 an engaging member pivotally mounted on said bracket, the pivotal connection being movable substantially in parallelism with said face to permit movement of said member along said face, and spring means arranged to be placed under tension by movement of said member along said face while subjected to pressure.

Signed by me at New York this 9th day of February, 1924.

WILLIAM H. BENEDICT.
